United States Patent Office.

WILLIAM W. WRIGHT AND JOHN BOODY, OF ELLSWORTH, NEW YORK.

Letters Patent No. 65,523, dated June 4, 1867.

IMPROVED BOLT-CUTTER.

The Schedule referred to in these Letters Patent and making part of the same.

TO ALL WHOM IT MAY CONCERN:

Be it known that we, WILLIAM W. WRIGHT and JOHN BOODY, of Ellsworth, in the county of St. Lawrence, and in the State of New York, have invented certain new and useful improvements in Bolt and Rivet-Cutters; and do hereby declare that the following is a full, clear, and exact description thereof, reference being had to the accompanying drawings, and to the letters of reference marked thereon.

In the annexed drawings, making part of this specification, A represents a steel bar, with a handle formed upon one end, and a jaw with a cutting edge upon the other. This bar may be made of iron, provided a steel jaw be provided, or a plate of steel is secured upon the jaw to form a cutting edge upon. C and D represent two metallic plates, similarly constructed, which are secured upon each side of the bar A, (only a portion of the plate D being seen.) B represents a metallic bar with a steel cutting edge upon a jaw similar to that upon bar A. This bar B is pivoted between the two plates C and D, the end between the plates being pressed downward by means of a spring, F, and upward by means of the cam end of a lever-handle, E. The handle E is pivoted at its cam end between the plates C and D, as represented. The screw G confines the spring F to the plates, and at the same time acts as a pivot for the bar B.

When the spring F presses the inner end of the bar B down, said bar at the same time pressing upon the cam end of lever E throws its outer end up. When the handle E is thrown up the two jaws are apart and ready to receive the bolt between them which is to be cut. The two handles being brought together the jaws close with a shear as well as a draw cut, severing the bolt with ease and dispatch.

By the use of the plates upon each side of the bars the bar B is held securely in its place, and its jaw is compelled to move and cut directly toward the jaw of bar A, without any possibility of veering to one side or the other.

Having thus fully described our invention, what we claim as new, and desire to secure by Letters Patent, is—

The combination and arrangement of the bars A and B, lever E, plates C and D, and spring F, constructed and operating in the manner and for the purpose specified.

In testimony that we claim the foregoing we have hereunto set our hands and seals this 17th day of April, 1867.

WM. W. WRIGHT,
JOHN BOODY.
